PLASMA FLAME GUN

Walter A. Siebein, Oakside Drive, Smithtown, N.Y., and
Anthony J. Rotolico, 80 Lakeview Ave., Lynbrook,
N.Y.

Filed Mar. 28, 1962, Ser. No. 69,464

Term of patent 14 years

(Cl. D62—2)

FIG. 4

FIG. 3

FIG. 1 is a side elevational view of a plasma flame gun showing our new design, the opposite side being substantially a mirror image thereof;

FIG. 2 is a front elevational view;

FIG. 3 is a top plan view, and

FIG. 4 is a bottom view.

We claim:

The ornamental design for a plasma flame gun, as shown and described.
